RAYMOND DEE YORK, OF PORTSMOUTH, OHIO.

PROCESS OF ROLLING BLANKS FOR I-BEAMS OR GIRDERS.

SPECIFICATION forming part of Letters Patent No. 728,349, dated May 19, 1903.

Application filed April 5, 1902. Serial No. 101,510. (No model.)

To all whom it may concern:

Be it known that I, RAYMOND DEE YORK, a citizen of the United States, residing in Portsmouth, Scioto county, Ohio, have invented certain new and useful Improvements in Processes of Rolling Blanks for I-Beams or Girders, of which the following is a specification.

My invention relates to an improved process of rolling blanks for flanged structures, such as I-beams or girders; and the object of my invention is to improve upon processes heretofore devised for rolling blanks for such structures and to allow the yielding or reduction of the web portion of the blank substantially unimpeded by the metal in the flange portions.

My improved process is fully disclosed in this specification, and suitable apparatus is described therein and shown in the accompanying drawings for carrying out my process.

In the accompanying drawings, Figure 1 is a side view of portions of a mill embodying my improvement. Fig. 2 is a horizontal section of the same, taken at the plane of the dotted line 2 2, Fig. 1.

Similar characters of reference designate corresponding parts in both figures.

The framework A of the mill may be of any suitable character. As shown, it comprises side frames a' a², mounted upon a bed a³, and will have tie-pieces extending between the side frames.

B' B² are horizontal rolls arranged one above the other and provided with a number of passes. The lower roll B' is journaled in fixed bearings, whereas the upper roll B² is journaled in bearing-boxes capable of moving vertically in housings formed in the side frames. Any suitable means may be provided for securing a relative adjustment between these rolls. The rolls B' B² are shown as having three passes 1, 2, and 3. The pass 1 is of ordinary configuration and is adapted to produce a reduced slab or ingot having parallel top and bottom and sides bulging outwardly to points about midway of the top and bottom. The pass 2 comprises a central cylindric portion b³. At the sides of this central cylindric portion b³ are two adjacent collar or flange-like portions b⁴, having adjacent sides b⁵, which are inclined so as to diverge

toward their peripheries. At the other sides of the collar or flange-like portions are cylindric portions b⁶, which may be of approximately the same diameter as the central cylindric portion b³, although this is not essential. Beyond the cylindric portions b⁶ are collar or flange-like portions b⁷. The adjacent sides of each pair of collar or flange-like portions b⁴ b⁷ are inclined so as to diverge toward their peripheries. The collar or flange-like portions b⁷ of the two rolls B' B² are shown as of such diametrical size that when the rolls are properly adjusted those of each roll contact with those of the other; but this is not an essential feature. The collar or flange-like portions b⁴ are diametrically smaller. Hence a space is left between those portions of the two rolls. It will be seen that this pass 2 is adapted to transform the reduced ingot or slab resulting from the operation of pass 1 into a blank or partly-formed I-beam or girder having, as usual, flange-like portions, but having in addition to these flange-like portions a web which is thickened longitudinally along its middle portion on both sides. The pass 3 has a central cylindric portion b⁸, which is quite large diametrically. On each side of this cylindric portion are cylindric portions b⁹, which are diametrically smaller. Beyond one of the cylindric portions b⁹ is one of the collar or flange-like portions b⁷, already mentioned, and beyond the other cylindric portion b⁹ is a collar or flange-like portion b¹⁰, which not only forms part of pass 3, but also part of pass 1. The collar or flange-like portion b¹⁰ is shown as of the same diametrical size as the collar or flange-like portion b⁷. The sides of the cylindric portion b⁸ and adjacent sides of the collar or flange-like portion b⁷ b¹⁰ are inclined so as to diverge toward their peripheries. The blank produced by pass 2 facilitates the subsequent shaping by pass 3. In the latter operation the central thickened portion of the blank produced by pass 2 is thinned down to the proper dimension, and this results in widening the web and forcing the flanges of the I-beam or girder apart to the proper distance for a finished I-beam or girder blank. In Fig. 1 the shape of this blank and its position in pass 3 are indicated. The strain exerted on the metal in passes 2 and 3 is materially less, es-

especially at the flanges of the I-beam or girder blank, by reason of the fact that in pass 2 there is left in the blank a thickened central portion, which is the principal part operated 5 upon in pass 3.

E' E² E³ E⁴ designate upright rolls, which for convenience may hereinafter be designated as "long" upright rolls. F' F² are other upright rolls, which for convenience 10 may hereinafter be referred to as "short" upright rolls. The short upright rolls F' F² are intended to have fixed positions and to have no movement of any kind except rotary movement. The long upright rolls E' E² E³ E⁴ 15 are, however, intended to be supported in adjustable bearings, so as to be capable of movement lengthwise of the axis of the rolls B' B² for the purpose of coacting with the different passes 1, 2, and 3 of those rolls. As 20 these rolls and the means for supporting and adjusting them are fully illustrated in an application for United States Letters Patent which I filed on the 22d day of January, 1902, and which has been designated series of 1900, 25 Serial No. 90,733, I will not illustrate or describe anything more than these rolls themselves.

It will thus be seen that according to my improved process the blank is first rolled to 30 reduce the metal along one or more longitudinal lines, leaving a thickened web portion and flanges separated thereby, and then said thickened web portion is rolled and reduced, whereby the yielding and reduction of said 35 portion is practically unimpeded by the metal in the flange portions. The thickened web portion is therefore reduced separately from the flange portions and with decreased resistance and the lateral flowing of the metal of 40 the web is facilitated independently of the metal in the flanges.

What I claim as new, and desire to secure by Letters Patent, is—

1. The improved process substantially as herein described, of rolling a blank for an I- 45 beam or girder, which consists in first rolling the blank to less than its intended width and with thickened portions disposed longitudinally on opposite sides of the web, intermediate of the lateral boundaries of the latter, 50 and then rolling said thickened portions to widen out the web and thereby produce the completed blank.

2. The improved process substantially as herein described, of rolling a blank for an I- 55 beam or girder, which consists in first rolling the blank to less than its intended width and with longitudinal thickened portions disposed equally on both sides of the web, intermediate of the lateral boundaries of the latter, 60 and then rolling and reducing said thickened portions to widen out the web and thereby produce the completed blank.

3. The improved process substantially as herein described, of rolling blanks for flanged 65 structures, which consists in first rolling and reducing the metal along one or more longitudinal lines, so that there will be flanges and a thickened web portion separated by portions of the web, and then rolling and reducing the said thickened web portion whereby 70 the yielding and reduction of said portion is substantially unimpeded by the flange portions.

In testimony whereof I have signed my 75 name to this specification in the presence of two subscribing witnesses.

RAYMOND DEE YORK.
